SUN VISOR

Clarence E. Stow, Kansas City, Mo., assignor of
one-half to Jacob J. Waspi and Effie M. Waspi,
both of Kansas City, Mo.

Application October 15, 1951, Serial No. 16,940

Term of patent 7 years

(Cl. D57—1)

To all whom it may concern:

Be it known that I, Clarence E. Stow, a citizen of the United States, residing at Kansas City, in the county of Jackson and State of Missouri, have invented a new, original, and ornamental Design for a Sun Visor, of which the following is a specification, reference being had to the accompanying drawing, forming a part thereof, wherein:

Fig. 1 is a top plan view of a sun visor, showing my new design.

Fig. 2 is a side elevational view thereof.

Fig. 3 is a front elevational view thereof.

Fig. 4 is a fragmentary, cross-sectional view taken on line IV—IV of Fig. 3 showing the sun visor in one position; and

Fig. 5 is a fragmentary, cross-sectional view, but showing the visor element slightly tipped

downwardly.

I claim:

The ornamental design for a sun visor, as shown.

CLARENCE E. STOW.
